UNITED STATES PATENT OFFICE.

CLARENCE E. AXLINE, SR., OF BRYANT, ILLINOIS.

GATE-LATCH.

1,387,961.

Specification of Letters Patent. Patented Aug. 16, 1921.

Application filed June 25, 1920. Serial No. 391,791.

To all whom it may concern:

Be it known that I, CLARENCE E. AXLINE, Sr., a citizen of the United States, residing at Bryant, in the county of Fulton and State 5 of Illinois, have invented certain new and useful Improvements in Gate-Latches; and I do hereby declare that the following is a full, clear, and exact description of the invention, which will enable others skilled in 10 the art to which it appertains to make and use the same.

My invention relates to improvements in gates, being directed more particularly, however, to an improvement in a lock or 15 latch for a gate, being particularly fitted for so-called farm gates.

The main object of my invention is to provide a latch for a gate that will automatically engage a keeper and positively secure 20 the gate when closed, and in either of its open positions substantially parallel to the drive-way or road which the gate controls.

Another object is the provision of a simple latch mechanism that may be operated by 25 the lifting of a bar or similar part by hand as in passing on foot through the gate-way or that may be operated from a vehicle, the gate being maintained in either of its open positions even through strong winds may be 30 prevailing.

In order that my invention may be clearly understood I have provided the accompanying drawings forming a part hereof showing a preferred arrangement of the gate-latch mechanism, it being understood that 35 the invention is susceptible of various changes without departing from the spirit and intent thereof.

Figure 1 is a side elevation of a gate 40 showing my invention in connection therewith.

Fig. 2 is a plan of part of the gate and part only of the invention.

Fig. 3 shows in perspective a part only of 45 the invention in two of the positions of the gate, and

Fig. 4 shows in perspective a keeper for a latch-bar shown in Fig. 1.

1 and 2 indicate the usual posts of a fence, 50 between which the gate 3 is located. The post 2 has secured thereto supporting brackets 4 and 5 common to many gate structures, while 6 and 7 is a pair of loops, one of which is shown in Fig. 2, to support the gate 55 3 upon said brackets, being well known structures, a sleeve or thimble 7' being pref-

erably clamped in each loop to engage over each of the brackets, but one of which is shown.

8 is a latch-bar pivoted at one end and to 60 the middle brace 3' of the gate, its other end adapted to engage a keeper 9 attached to the post 1, shown clearly in Fig. 4, the opposite portion of the said keeper being inclined upwardly from each side at 10 for 65 guiding the latch-bar upwardly from either direction, a notch 11 receiving the bar into it in a customary manner for holding the gate closed.

12 indicates a pin which may extend 70 through the said latch-bar constituting a grasping-piece at either side of the gate.

At 13 is a member constituting a latch for the gate in either of its open positions as well as jointly with the latch-bar at the 75 closed position. This member is most clearly shown in Figs. 2 and 3. It consists of a U-shaped part pivoted at its extremities to the rear edge of the gate just above one of the brackets 4 and 5, preferably the latter, being 80 adapted to rise and fall. In its lower edge is a series of three notches 14, 15 and 16, the notches 14 and 16 being made in the extremities of the member opposite one another, Figs. 1 and 3, while the notch 15 is in the 85 yoke-portion of such member as shown in Fig. 3. Extending vertically from one of the extremities is an arm 17 to which is loosely attached a rod 18 whose opposite end is loosely attached to end of a lever 19 pivoted between its ends on the gate 3, Fig. 1.

20 is a link connected at one end to the opposite end of the lever 19 and at its other end to the latch-bar 8.

In the positions shown in Fig. 1, in which 95 the gate is closed, gravity holds the latch-bar 8 in the notch 11 of the keeper 9, gravity also holding the member 13 in engagement with the bracket 5 through the notch 15.

In closing the gate the latch is lifted to 100 disengage the member 13 from the bracket 5; as to either 14, 16. As this is done, that part of the said member between the notches 14 and 15, or that lying between the notches 15 and 16 will ride upon the bracket holding 105 the latch raised until the gate is opposite or nearly opposite the keeper 9, whereupon both the latch and member will descend to the locking position.

The relation of the described parts is such 110 that upon lifting the bar 8 and consequently the link 20 the lever 19 will be swung on its

pivot and the rod 18 pulled to lift the member from engagement with the bracket 5. This permits the gate to be swung open in either direction, which, upon reaching a position substantially at right angles to its normal or closed position, will be held by the member engaging the bracket by means of one or the other of the notches 14, 16. This has been illustrated in Fig. 3. The bar 8 having, of course, been released, that part of the member between two of the notches will rest and travel upon the bracket until such time as the notch coming opposite the bracket will permit the latter to descend and effectively secure the gate.

It is clear that the gate cannot be affected by winds and must remain in the position to which it is swung until released by lifting the bar 8, by grasping the arm 17, or by pulling upon the rod 18. Of course, other means may be used in place of the bar 18, though this is found to answer as a simple form of device to be grasped by the hand.

Any form or arrangement of operating mechanism may be attached to my latch structure described by which to operate the latter from a vehicle at either side of the gate, as may be understood, but what I claim and desire to secure by Letters Patent is:

30 1. The combination with a gate, a supporting part on which it is hingedly mounted, a keeper for the opposite end of the gate, and a latch to engage it, of a member serrated at its lower edge adapted to swing

about said supporting part and adapted to 35 engage the same, of a mechanism connecting the latch and said member adapted to operate the latter in the movement of said latch.

2. The combination with a hinged gate 40 and a latch therefor, and a member mounted pivotally upon the gate having a series of notches adapted to engage a stationary portion on the support upon which the gate is hung adapted to secure the latter in any 45 one of several positions, of mechanism pivotally mounted on the gate connected to or between the latch and said member adapted when the latch is raised to disengage the member.

3. The combination with a gate, a support to which the gate is hinged, a member pivotally mounted on the gate having a series of notches any one of which is adapted to engage the support, and a latch for the gate, 55 of a lever arm pivoted between its end on the gate, a link connecting one end of the lever and the latch, and a rod connecting the other end of the lever with the member adapted when the latch is raised to disengage the member from the support.

In testimony whereof I affix my signature in presence of two witnesses.

CLARENCE E. AXLINE, Sr.

Witnesses:

PLENNIE SARFF,
F. E. CARPENTER.
